CLAIM

The ornamental design for a heat-protective arm and hand glove for hot food service, as shown.

DESCRIPTION

FIG. 1 is a front-elevational view of a heat-protective arm and hand glove for hot food service, showing my new design;

FIG. 2 is a left-side-elevational view thereof;

FIG. 3 is a rear-elevational view thereof;

FIG. 4 is a top-plan view thereof; and

FIG. 5 is a bottom-plan view thereof.
